(57) **CLAIM**

The ornamental design for a bath dispenser, as shown and described.

DESCRIPTION

FIG. 1 is a top and side perspective view of a bath dispenser showing a new design;

FIG. 2 is a front view thereof;

FIG. 3 is a back view thereof;

FIG. 4 is a right side view thereof;

FIG. 5 is a left side view thereof;

FIG. 6 is a bottom view thereof; and,

FIG. 7 is a top view thereof.

The dashed lines in the drawings show environmental conditions only and form no part of the claimed design.
